UNITED STATES PATENT OFFICE

EDGAR COCKS, OF LOS ANGELES, CALIFORNIA

FOLDING BED END ATTACHING DEVICE

Application filed April 14, 1931. Serial No. 530,084.

This invention relates to a device for attaching an end to the frame of a folding bed of the concealable type. More particularly the invention relates to a device which not only serves for attaching the end, but also to mount it so that it may be moved in relation to the frame to a folded position paralleling the frame, and also a position perpendicular to the frame, as the bed is moved into and out of its position for use.

The principal object of the invention is the provision of an improved device of the indicated character which will be of efficient and substantial design, and which will enable the parts of a folding bed to be conveniently and easily moved in relation to each other for the purposes mentioned.

The nature of the invention and its distinguishing features and advantages will appear when the following specification is read in connection with the accompanying drawings, in which

Figure 1 is a section of a portion of a folding bed frame, the foot end and the attaching device embodying features of the invention;

Figure 2 is a section on the line 2—2 of Figure 3;

Figure 3 is a view looking at the under side of a portion of the bed frame and showing the foot end thereof in folded position, and parts of the frame and foot end being broken away.

The present invention essentially involves a frame 10 of a folding bed, and one of the ends, namely, the foot end 11 of the bed in the present instance. It is to be understood that the frame 10 supports the usual spring, mattress and bedding, and is mounted for movement from a horizontal position for use into a substantially vertical position within a recess or chamber in which the bed is to be concealed.

The device of the present invention, as stated, serves for attaching the foot end 11 to the frame 10 and also serves to so mount the end that it may be moved in relation to the frame 10 to a position substantially perpendicular to the frame, as shown in Figure 1, and also to a position paralleling the frame

at the under side thereof, as shown in Figures 2 and 3.

The device includes attaching members 12 each of which consists of an elongated piece of metal of suitable length. Each member 12 has holes therein to accommodate fastening elements 13 which serve for fastening members 12 to the frame 10. The members 12 are secured respectively to the opposite side rails of the frame 10. Use is made of rigid members or arms, there being a first arm 14 and a second arm 15, the latter being shorter than the former. A pair of arms 14 and 15 is arranged between each attaching member 12 and the side member 16 of the foot end 11, and the arms 14 and 15 are also arranged in spaced relation with respect to each other. One end of the arm 14 is pivotally connected as at 17 with the related member 12, and the opposite end thereof is pivotally connected as at 18 with the related side member 16. The arm 15 has one end thereof pivotally connected as at 19 with the related member 12 in advance of the pivot 17, and the opposite end of said arm 15 is pivotally connected as at 20 with the related side member 16 above the pivot 18. A short link 21 has one end thereof pivotally connected as at 22 with each member 12 at one side of a line extending through pivots 17 and 19 and disposed between the pivots 17 and 19. A tension spring 23 has one end connected as at 24 with the free end of the link 21 and its opposite end is connected as at 25 with the related arm 14 between its ends. Each of the attaching members 12 has studs or stops 26 and 27, respectively. The arms 15 co-operate respectively with the studs 26 to limit the motion of the foot end 11 to a position in which the foot end will be disposed perpendicular to the frame 10, as the bed is swung down for use. It will therefore be understood that the foot end of the frame 10 will be supported by the foot end 11 by virtue of the arms 15 and the studs 26. The arms 14 serve to brace the foot end 11. The bed frame 10 is moved to the horizontal position by grasping the top of the foot end 11 which will bring the foot end 11 into proper posi-

100

tion with respect to the frame 10, as shown in Fig. 1.

When the frame 10 is moved to its vertical position, the foot end 11 will assume a position substantially paralleling the frame 10.

- As the foot end 11 moves into the last mentioned position, the links 21 encounter the stops 27, respectively, and thus limit the movement of the links, so that the springs 23 will be disposed substantially parallel to the arms 14, as shown in Fig. 2. The springs 23 will be compelled to assume positions which will not interfere with the easy movement of the foot end 11 in relation to the frame 10, as the latter is swung from the vertical position to horizontal position. It will also be apparent that the springs 23 as connected with the links 21 will maintain the arms 15 in contact with the studs 26 with the foot end 11 disposed perpendicular to the frame 10.
- The springs 23 will be under tension at all times, and will aid in moving the foot end 11 to its set-up and folded positions in relation to the frame 10 and to retain it in such positions.

25 I claim:

1. A folding bed end attaching device comprising, attaching members respectively at the sides of said bed end, first and second rigid members arranged between each attaching member and the bed end, and also arranged in spaced relation with respect to each other, and pivotally connected with the attaching member and the bed end, a link 30 pivotally connected at one end with each attaching member, a spring having its ends connected respectively with the free end of each link and the related first rigid member, studs on said attaching members for the second rigid members to cooperate therewith to retain the bed end substantially perpendicular to the attaching members, and stops on the attaching members to cooperate respectively with the links to limit the movement of the latter, so that the springs connected therewith will be disposed substantially parallel to said first rigid members when the bed end is in folded position.

2. In combination, a folding bed end, a bed frame, a link having one end pivotally connected with means on the frame, an arm having one end pivotally connected with means on the frame and its other end pivotally connected with means on said end, a spring having its ends connected respectively with the free end of said link and said arm between the ends of the latter, and means projecting from said frame to cooperate with said link to limit its movement in one direction to a position so that the spring will be disposed substantially parallel to the arm when the bed end is in folded position.

3. In a device for attaching a bed end to a frame for movement into and out of folded relation thereto, an attaching member, a link

having one end pivotally connected with said member, an arm having one end pivotally connected with said member, a spring having its ends connected respectively with said link and arm, and a stop on said member to cooperate with said link to limit its movement in one direction to a position so that the spring will be disposed substantially parallel to said arm.

4. A folding bed end attaching device comprising, attaching members respectively at the sides of said bed end, first and second rigid members arranged between each attaching member and the bed end, and also arranged in spaced relation with respect to each other, the first rigid member being shorter than the second rigid member, and pivotally connected with the attaching member and the bed end, a link pivotally connected at one end with each attaching member, a spring having its ends connected respectively with the free end of each link and the related first rigid member, studs on said attaching members for the second rigid members to cooperate therewith to retain the bed end substantially perpendicular to the attaching members, and stops on the attaching members to cooperate respectively with the links to limit the movement of the latter, so that the springs connected therewith will be disposed substantially parallel to said first rigid members when the bed end is in folded position.

5. In a device for attaching a bed end for movement into and out of a folded relation with respect to a bed frame, a link pivotally connected with a frame member, a retaining arm interposing the bed end and frame member and pivotally connected with both, a brace member interposing the bed end and frame member and pivotally connected with both, the pivotal connection of the link being disposed at one side of a line between the pivotal connections of the arm and brace member with the frame between the latter connections, a tension spring having its ends connected respectively with said link and brace member, a stop on the frame to limit the pivotal movement of the retaining member in one direction, and a stop on the frame to limit the movement of the link in one direction, the provision and arrangement being such, that the spring will be under tension at all times to aid in moving the bed end to its set up and folded positions in relation to said frame and to retain it in such positions.
